UNITED STATES PATENT OFFICE.

DAVIS BROWN, OF BUCYRUS, OHIO, ASSIGNOR TO HADFIELD PENFIELD STEEL COMPANY, OF BUCYRUS, OHIO, A CORPORATION OF OHIO.

DRY PAN.

1,390,235.

Specification of Letters Patent.

Patented Sept. 6, 1921.

Original application filed December 14, 1917, Serial No. 207,043. Divided and this application filed December 20, 1918. Serial No. 267,651.

To all whom it may concern:

Be it known that I, DAVIS BROWN, a citizen of the United States, and a resident of Bucyrus, Ohio, have invented an Improvement in Dry Pans, of which the following description, in connection with the accompanying drawings, is a specification, like letters on the drawings representing like parts.

10 The present invention is an improved screen plate for dry pans, being a divisional of my prior application, Serial Number 207,043, filed December 14, 1917, upon the process of making the improved screen plates claimed herein.

As explained in said co-pending application, the screen bars or grids must withstand very heavy strains and cast iron has been found insufficient for this work and the 20 present invention consists in the discovery of a practical method of building the cast iron framework with rolled steel bars. In manufacturing the screen plates of my present invention I provide the usual pattern for casting the frame of the screen around the outer side, but I so arrange an intermediate section for supporting the inner ends of the grids as to form same first in 25 relatively thin metal portions capable of springing during the cooling of the frame without danger of distorting the heavier outside rims. I accomplish this by first forming the middle section or partition in a usual manner and then fitting a core 30 through the middle section of the mold for this middle partition, applying the steel bars throughout the mold in desired proximity with their outer ends in line to fit within the casting and the inner ends within one of the 35 relatively thin middle partitions cast by the application of the core through the middle mold as above explained. The iron is then cast to form the frame, firmly engaging and holding the respective ends of the steel 40 grids, and permitted to cool. During this cooling, the contraction of the frame may draw the inner thin partitions somewhat, but said inner partitions are so formed as to spring and permit this contraction. There- 45

50 after the middle section is again fitted in a mold, and the space from which the core has been removed is filled up with molten iron, as a separate casting. Preferably the second casting is made to dovetail with or interlock about the two thin members 55 which were originally made for the central partitions. The result is an improved screen, with an iron frame and steel grids or bars, which has been made in a feasible, practicable and commercial manner at a 60 minimum of cost, automatically taking care of the normal tendency of the metal to shrink or contract when cooling down in a mold, and furthermore preventing the steel bars from buckling when cooling. 65 Referring to the drawings illustrating a preferred embodiment of the invention, Figure 1 is a view partly in cross section of a dry pan;

Fig. 2 is an enlarged view of one of the 70 screen plates;

Fig. 3 is a cross-sectional view on the line 3—3 of Fig. 2;

Figs. 4 and 5 and 6 are detailed views of the connections between the steel grid bars 75 and the cast iron frame.

I have shown in the drawings, for illustrative purposes, the type of dry pan such as that illustrated in patent to R. C. Penfield, No. 974,818, dated November 8, 1910, 80 wherein the dry pan is built upon the foundation or framework 1, having suitable side frames 2, a central drive shaft 3, suitable mechanism for supporting the mullers 4, the main grinding base or hub 5, radial 85 carrying flanges 6, and cylindrical rim 7 carrying the screen plates 8, arranged in segmental sections around the revolving pan.

Each screen section, as illustrated in Fig. 90 2 comprises a frame with the inner rim portions 10 and outer rim portions 11 in concentric arcs and of a size suitable for the diameter of dry pan in which they are to be employed. This section is further 95 formed with radial frame portions 12 and 13 are each formed as shown in Fig. 4 with a dovetailed recess as indicated at 14 to receive the correspondingly shaped end 15 of a steel grid bar 16. Preferably these recesses 14 are made in groups of three or four, four such being shown at 17, 17, 17, 17, in the drawings. This permits a set of four grid bars of the same length to be interchangeably fitted at appropriate sections 100 throughout the screen.

The dovetailing arrangement of the steel grid bars in the outer cast iron frame sec-

tions 12 and 13 as just described, is readily accomplished by fitting the bars therein before the central partition 20 is formed. As shown in Fig. 5, the inner ends of the steel bars 16 are similarly dovetailed and fitted into a thin spacing and carrying member 21 and 21, which members 21 are appropriately spaced from each other to permit the subsequent pouring of the iron to form the rest 10 of the middle partition 20. I prefer to form these thin divisional walls of irregular shape, such as, for example, on the curved lines 22, 22, in order to provide an interlocking when the rest of this middle partition member, 15 viz., the member 20, is cast therein.

The pattern is molded in the same in the usual way, then the pattern is withdrawn and a dry sand core, substantially of the form shown at 20, Fig. 2, and the steel bars, 20 16, are placed in the sand in their proper places. The mold is then closed and the cast iron poured around the bars 16 and the core in the place of the member 20. After cooling the casting is removed from 25 the sand and cleaned. The core being cleaned out leaves a space between the two division walls 21. In cooling, the cast iron frame shrinks closing in on the bars and forces them toward the center 30 and the center division walls 21, which being purposely lighter and weaker than the other and outer walls of the frame will spring or maybe break away from the main frame at the junction points 35 and this is what prevents buckling of the bars or weakening of the main frame when it contracts in cooling. The space between the two light division walls 21 permits them to spring toward or from each other and relieve the bars and the main frame of the 40 strains caused by the shrinkage of the cast frame on cooling down from the molten state. The bars are not subject to this shrinkage.

45 After cooling down and cleaning, the frame is again placed in the sand and the space between the two light center walls and additional space below these light partition walls is poured filling the vacant space between them and forming a permanent support beneath them, interlocking, solidifying, 50 and strengthening the center partition 20, 21 and 21 being a substantially solid member.

55 My invention thus combines steel grid bars with the cast iron frame, and secures the advantages of a simple and economical construction, presenting a screen plate with the desired increase in area of openings and 60 with steel grids which will outlast the cast iron many times over.

Fig. 6 illustrates, in cross-section, on the line 6-6 of Fig. 2, the present arrangement for the reinforcing poured metal 20

of the middle partition, where the same interlocks and bears upon the frame 10. It will be appreciated that other arrangements for interlocking, may be employed, if desired. The important feature of my invention consists in cast iron framework with 70 steel grid bars, preferably built so that the steel bars and cast iron framework may contract during cooling without unduly distorting the same or buckling the bars. I prefer to form one of the cast iron supports 75 for the steel grids thinner than the other to permit it to spring, as above explained, and then to strengthen this thinner supporting member by an additional bracing frame; preferably cast thereon and interlocking therewith. In the form shown, this thinner member subsequently strengthened and reinforced, is the middle supporting bar for the screen plate, and it could as well be one of the side members, if desired. 80 85

My present invention is further described and defined in the form of claims as follows:

1. A screen plate for dry pans, of the kind described, consisting in a framework of cast iron, steel grid bars being cast with the framework, said framework including a middle partition supporting the inner ends of the steel grid bars, said middle partition being composed of relatively thin cast iron 90 members supporting and spacing the inner ends of the bars and an interposed supporting, spacing and strengthening member.

2. A screen plate for dry pans, of the kind described, comprising a framework of cast 100 iron including relatively thick side plates and a relatively thin center plate composed of relatively thin members having an interposed spacing and strengthening member, steel grid bars extending between said plates 105 and having the ends thereof intimately associated with said plates.

3. A screen plate for dry pans, of the kind described, including a framework of cast iron having a relatively thick side plate and 110 a pair of relatively thin center plates, spaced apart from each other, a plurality of parallel dovetails arranged longitudinally of said side plate, a single dovetail arranged longitudinally of the said center plate, a plurality of groups of steel grid bars extending between the plates, one group in each of the parallel dovetails, and a strengthening bar arranged between the pair of relatively thin center plates.

In testimony whereof I have signed my name to this specification in the presence of two subscribing witnesses.

DAVIS BROWN.
